A. E. RHOADES.

STARTING AND STOPPING MECHANISM FOR LOOMS.

APPLICATION FILED MAY 19, 1908.

904,450.

Patented Nov. 17, 1908.

UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

STARTING AND STOPPING MECHANISM FOR LOOMS.

No. 904,450.

Specification of Letters Patent.

Patented Nov. 17, 1908.

Application filed May 19, 1908. Serial No. 433,704.

To all whom it may concern:

Be it known that I, ALONZO E. RHOADES, a citizen of the United States, and resident of Hopedale, county of Worcester, State of Massachusetts, have invented an Improvement in Starting and Stopping Mechanism for Looms, of which the following description, in connection with the accompanying drawing, is a specification, like letters on the drawing representing like parts.

This invention relates to mechanism for starting and stopping the operation of a loom, and it has for its particular object the improvement of certain details of construction in the apparatus forming the subject-matter of United States Patent No. 867,934, granted to G. B. Ambler, October 8, 1907. In the apparatus therein shown the power shifting device is a friction clutch, one member of which is fast on the driving shaft while the other member is loose on said shaft and movable toward and from the fast member. The hub of the loose member is annularly grooved to receive a follower fixedly secured to the yoke-like portion of a laterally movable lever provided with a sleeve-hub fulcrumed on a fixed, vertical pivot-pin, and the arms of the yoke-like portion are slotted to receive loosely opposite radial studs on a collar slidably mounted on the driving shaft. Setting of the clutch is effected by movement of the collar against the adjacent face of the hub of the loose member of the clutch, and its release is effected by the action of the follower in the groove of said hub.

It has been found in practice that sometimes when the clutch is set the studs on the collar act upon the slotted yoke-arms in such manner as to slightly twist or turn the follower so that it bears on the side of the annular groove in the hub of the loose member of the clutch, the friction thereby generated heating the adjacent parts and a considerable portion of the laterally movable clutch-controlling lever, this heating and the unnecessary wear being objectionable.

In my present invention I have obviated any tendency to generate friction and heat by mounting the upright pivot-pin of the yoke-like portion of the controlling lever on a fixed fulcrum at right angles to the pivot-pin, said fulcrum lying in the plane of the path of movement of the lever. By this

construction the yoke-like portion is enabled to adapt itself to slight irregularities, so that if there is any tendency of the slotted yoke-arms to bind on the studs of the sliding collar the yoke can rock slightly on the fixed fulcrum, thereby relieving such binding and obviating friction and the attendant wear and heating.

The novel features of my invention will be fully described in the subjoined specification and particularly pointed out in the following claims, and inasmuch as I have illustrated my invention in connection with the Ambler patented structure referred to only so much of the latter will be specifically described as may be necessary to a clear understanding of my improvement.

Figure 1 is a left hand side elevation of the starting and stopping mechanism of a loom with my invention applied thereto, the parts being shown in the position assumed when the loom is running; Fig. 2 is a top plan view of the portion of the mechanism embodying my present invention.

The breast-beam 2, main driving-shaft 3, crank-shaft 4, the fast member 7 of the friction clutch fixedly secured on the driving shaft 3, the coöperating member 8 loosely mounted on said shaft and movable toward and from the fast member, the latter having a suitable facing 9 of leather or other suitable material, Fig. 2, the hub 8^x of the loose member 8 (shown as a belt pulley) having an annular groove 12, the follower 13 traveling therein and fixedly secured to the yoke-like portion 14 of the laterally movable clutch-controlling lever 15, and the sleeve-hub 16 of said yoke-like portion 14 are and may be all substantially as in said Ambler patent. So, too, the yoke-arms are slotted at 19 to receive loosely opposite studs 20 extended radially from the collar 21 slidably mounted on the shaft 3 adjacent the hub 8^x of the loose clutch member 8, as in said patent, lateral swinging movement of the lever 15 on its fulcrum (to be described) in one direction acting through the abutting faces of the collar and hub to set the clutch, release thereof being effected by action of the follower 13 in the groove 12 of the hub when the lever is swung in the opposite direction.

The swinging movement of the clutch-controlling lever 15 is effected in the same manner as in the Ambler patent, and by the

same mechanism, and as the same forms no part of my present invention, needs no further description herein further than to state that the free end of the lever is loosely connected with a stud 28 on a sleeve 29 movable at right angles to and toward and from the loom-side on the fixedly-supported bearing-rod 24.

In accordance with my present invention 10 the sleeve-hub 16 is fulcrumed on an upright pin 30 at right angles to the path of movement of the lever 15, the upper and lower ends of said pin being fixedly held in a bifurcated carrier 31 having extended from 15 it at right angles to said pin a fulcrum stud 32 which is rotatively mounted in an elongated bearing 33 forming part of a bracket 34, Fig. 1, fixedly secured on the part 22 of the framing, the sleeve-hub 16 being 20 positioned between the upper and lower ends of the carrier. The carrier 31 is thus mounted to rock slightly about a fulcrum, as 32, which by reference to Fig. 1 will be seen to be in the plane of the path of movement of the lever 15, and hence the yoke 14 and its pivot-pin 30 can also rock on the same fulcrum, while the operative swinging movement of said lever is effected about the pivot-pin 30 as a fulcrum. In order to clear 25 the carrier and its bearing 33 I have bent the lever 15 and connected it with the side of the yoke-portion 14, as at 15*, best shown in Fig. 2.

In the ordinary operation of the mechanism 30 the lateral or clutch-controlling swing of the lever 15 is effected about the pin 30 as a fulcrum just as if said pin were rigidly fixed in one position, as in the Ambler patented structure, but if at such time the follower 13 should tend to bear hard on the side of the annular groove 12, due to binding or improper action between the studs 20 and the slotted yoke-arms, then the lever 15, yoke 14, pin 30 and its carrier 31 all have a 40 slight angular movement upon the fulcrum 32 to relieve the binding. This relieving movement of the parts is very slight and in no way interferes with the proper operation 45 of the clutch or the clutch-controlling lever.

50 For convenience the pivot-pin 30 may be termed the main fulcrum for and about which the controlling lever swings in its clutch-operating movement, while the stud 32 may be termed an auxiliary or relieving 55 fulcrum, permitting the parts to move slightly about such fulcrum to relieve undue pressure or binding.

Having fully described my invention, what I claim as new and desire to secure by Letters Patent is:—

1. In a loom, a driving shaft, fast and loose clutch members mounted thereon, a clutch-controlling lever, a main fulcrum for and about which said lever is adapted to 65 swing to set or release the clutch, and an

auxiliary fulcrum about which said lever may rock slightly to prevent binding in its connection with the clutch.

2. In a loom, a driving shaft, fast and loose clutch members mounted thereon, a clutch-controlling lever, a main fulcrum for and about which said lever is adapted to swing to set or release the clutch, a carrier for said fulcrum, and a pivotal support for the carrier at right angles to the main fulcrum, said pivotal support serving as an auxiliary fulcrum about which the controlling lever may at times rock slightly.

3. In a loom, in combination, a power-shifting clutch, a controlling member therefor, a main fulcrum for said member located at right angles to its clutch-operating path of movement, and an auxiliary fulcrum about which both said member and the main fulcrum may rock to prevent binding.

4. In a loom, in combination, a power-shifting clutch, a controlling member therefor, a main fulcrum for said member located at right angles to its clutch-operating path of movement, and an auxiliary fulcrum at right angles to the main fulcrum and in the plane of the operative path of movement of said controlling member, whereby the said member may rock slightly on the auxiliary fulcrum at various points in its swinging path about the main fulcrum.

5. In a loom, in combination, a power-shifting clutch, a controlling member therefor, one member of the clutch having an annular groove, a follower traveling therein and fixedly mounted on the controlling member, and main and auxiliary fulcra for said member and located at right angles to each other, the clutch operating movement of the controlling member being effected about the main fulcrum, the auxiliary fulcrum permitting the controlling member to rock thereon to relieve binding between the follower and the annularly-grooved member of the clutch.

6. In a loom, a driving shaft, a clutch member fast thereon, a coöperating member loosely mounted on the shaft and slidably toward and from the fast member, said loose member having an annularly grooved hub, a coöperating follower, a clutch-controlling lever having a yoke-like portion on which the follower is rigidly secured, a clutch-setting collar loosely connected with the yoke-like portion, and a main fulcrum about which the lever is adapted to swing to set or release the clutch, combined with a carrier for the fulcrum, having a stud at right angles thereto, and a fixed bearing in which the stud may turn, said stud acting as an auxiliary fulcrum to relieve binding between the yoke-portion of the lever and the clutch or clutch-setting collar.

7. In a loom, in combination, a power-shifting clutch, a controlling lever therefor

having a sleeve-hub at right angles to its operating path of movement, a main fulcrum pin extended through the hub, a bifurcated carrier to which the ends of said pin are attached, a stud rigidly extended from the carrier in the plane of the operating path of movement of said lever, and a fixed bearing for and in which the stud is mounted to rock, said stud serving as an auxiliary ful-

crum for the controlling lever and its main 10 fulcrum.

In testimony whereof, I have signed my name to this specification, in the presence of two subscribing witnesses.

ALONZO E. RHOADES.
